UNITED STATES PATENT OFFICE

CHARLES A. SCHALLIS, OF LINCOLN PARK, NEW JERSEY, ASSIGNOR TO THOMAS A. EDISON, INCORPORATED, OF WEST ORANGE, NEW JERSEY, A CORPORATION OF NEW JERSEY

DESIGN FOR A COFFEE MAKER OR LIKE ARTICLE

Application filed August 6, 1930. Serial No. 36,579. Term of patent 14 years.

To all whom it may concern:

Be it known that I, CHARLES A. SCHALLIS, a citizen of the United States, and a resident of Ernestville, Lincoln Park, in the county of Morris and State of New Jersey, have invented a new, original, and ornamental Design for Coffee Maker or Like Article, of which the following is a specification, reference being had to the accompanying drawing, forming a part thereof.

In the drawing:

The single figure is a perspective view of a coffee maker or like article showing my new design.

The dominant feature of my design consists in the general outline of the coffee maker, which comprises a base 1 on which is mounted a body member 2 surmounted by a domed top 3, substantially as shown in solid lines, said base, body member and top being substantially circular in horizontal cross section.

I claim:

The ornamental design for a coffee maker or like article, substantially as shown and described.

CHARLES A. SCHALLIS.
